UNITED STATES PATENT OFFICE.

DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY.

FURNACE-WALL.

1,320,059.

Specification of Letters Patent. Patented Oct. 28, 1919.

Application filed October 9, 1917. Serial No. 195,542.

To all whom it may concern:

Be it known that I, DAVID S. JACOBUS, a citizen of the United States, residing at Jersey City, in the county of Hudson and State 5 of New Jersey, have invented certain new and useful Improvements in Furnace-Walls, of which the following is a specification.

The present invention relates to certain improvements in the construction of walls 10 for boiler furnaces and will be understood by reference to the accompanying drawings, in which Figure 1 is a side view, partly in section, of one adaptation of the invention; Fig. 2 is an enlarged view of the wall, 15 broken away, of Fig. 1; and Figs. 3 and 4 vertical sections of modifications of the arrangement shown in Figs. 1 and 2.

Similar reference numerals indicate similar parts in the several views.
20 In my application Serial No. 90,058 filed April 10, 1916, I have described means for supporting the front wall of a boiler setting where the weight of the wall is carried, in part, by struts spaced beneath the wall and 25 at intervals along the front of the stoker so that they do not interfere with the carrying of a uniform bed of fire from side to side of the furnace. In that construction I employ special refractory blocks in the wall which 30 interlock with tie pieces to maintain the alinement of the wall. According to the present invention the wall is made in sections, the lower section being supported on the stoker mechanism and the upper section 35 on a cross beam. The struts described in my previous application may or may not be used in connection with the present invention.

For the purpose of explaining one adaptation of the invention I have shown in Fig. 40 1 the front wall of a setting of a Stirling boiler; the front bank of tubes 1 of said boiler together with the front steam and water drum 2 and mud drum 3 being illustrated. The boiler is shown as fired by an 45 underfeed stoker which comprises the twyer boxes 4 and a ledge plate 5, the latter consisting of the top plates of the twyer boxes and fuel magazines or retorts.

The front wall is built in two parts or 50 sections, the lower designated generally by the numeral 6 and the upper by the numeral 6'. The weight of the lower section 6 is carried directly by the stoker ledge plate 5

and this weight is so reduced that it may not be necessary to employ the supporting struts 55 described in my application above referred to. This section which rests directly on the stoker mechanism is held in alinement by means of the special tile pieces or refractory blocks 7, two courses of which are shown, 60 and metallic tie pieces 8 having heads 8' which engage grooves or recesses in the blocks as more fully described in my said application Serial No. 90,058. Near their front ends the tie pieces 8 are formed with 65 projecting lugs 11 and these lugs, at their upper and lower projecting ends are engaged by a channel iron 9 and a Z-bar 10, respectively. The channel iron 9 is secured to the web of an I-beam 12, and the Z-bar 70 is secured to the base or lower flange of said beam as indicated in Fig. 2. The beam 12 is supported in the side walls of the setting and extends across the space formed by an 75 inset in the lower section of the wall, and is the sole support of the upper section 6' of the wall.

The refractory blocks 7 and the metallic tie pieces 8 are arranged to allow the section 80 6 of the wall to expand upward and sidewise without inducing an undue amount of strain, by reason of the expansion of the wall. Holes 13, for ventilation are drilled 85 in the web of the I-beam and the small amount of air which enters through these holes assists in keeping cool the cast iron tie pieces and their supports, and also the I-beam.

The upper part of the wall, which is of 90 greater height than the lower part, is held in alinement by courses of special tile pieces or refractory blocks placed in two double rows at 14 and 15, and metallic tie pieces 16 similar to the tie pieces 8.

The lower part of the wall can expand up 95 and down freely, a sliding joint 17 being provided between it and the upper part of the wall. In actual construction there is less space at the sliding joint than is indicated in the drawing; in fact the bricks will 100 be laid in close contact and the soot, dust and slag from the coal burned on the stoker will seal the joint.

Fig. 3 illustrates a modification in which 105 the special tiles or blocks 7 are at a level below the I-beam 12, and the projecting up-

per and lower ends of the lugs 11 engage angles above and below the blocks which are secured, respectively, to the base or lower flange of the I-beam 12 and to the outer 5 metallic casing 18. In this form two rows of ventilating holes 19 are shown in the I-beam instead of a single row as in Figs. 1 and 2, and the cool air is shown as entering one set of holes and leaving the other. There 10 will usually be sufficient leakage at the expansion joint 17 and through the brick work to cause all of the ventilating air to flow inward through the holes. Two rows of ventilating holes 20 are drilled in the casing 15 in front of the projecting ends of the tie pieces. 8.

In the construction illustrated in Fig. 4, two courses 21 and 22 of special tile pieces or blocks are used at different levels in the 20 wall section 6. In this form the upper and lower projecting ends of the lugs 11 on the tie pieces 8 of the set of tiles 21 engage Z-bars immediately below and above the special tiles, said bars being rigidly secured to 25 the outer metallic casing 18. The lugs on the tie pieces of the tiles 22 engage Z-bars which are rigidly secured to the I-beam 12. Each course of special tiles is independently 30 ventilated by air which flows through the holes 23 and 24.

What I claim and desire to secure by Letters Patent of the United States is:—

1. A furnace comprising a stoker, a wall built in sections one of which sections is supported on the stoker; and a support independent of the stoker for the other section, said sections being so arranged that there can be relative movement between them to form an expansion joint. 40
2. A furnace comprising a stoker, a wall built in sections one of which sections is supported on the stoker, and a support independent of the stoker for the other section, both of said sections having courses with 45 special tiles, fixed members, and metallic tie pieces engaging said tiles and said fixed members to assist in holding the wall in proper alignment.

3. A furnace comprising a stoker, a wall built in sections one of which sections is supported on the stoker, and a support independent of the stoker for the other section, said upper section having courses with special tiles, a fixed member and metallic tie pieces engaging said tiles and said fixed member to assist in holding the wall in proper alignment. 50
55

4. A furnace comprising a stoker, a wall built in sections one of which sections is supported on the stoker, and a cross beam independent of the stoker on which the other section is supported. 60

5. A furnace comprising a stoker, a wall built in sections one of which sections is supported on the stoker, a cross beam in- 65

dependent of the stoker on which the other section of the wall is supported, said sections being constructed and arranged to permit a relative movement between them in a generally vertical plane. 70

6. A furnace comprising a stoker, a wall built in sections one of which sections is supported on the stoker, a support independent of the stoker for the other section of the wall, one of said sections having courses 75 with special tiles, a fixed member, and metallic tie pieces engaging said tiles and said fixed member to assist in holding the wall in proper alignment, the projecting ends of said tie pieces being in an inclosed space, and 80 means for ventilating said space.

7. A furnace comprising a stoker, a wall built in sections, one of which sections is supported on the stoker, a beam independent 85 of the stoker upon which the upper section of the wall is supported, special tiles in the lower section, and metallic tie pieces engaging said tiles and said beam to assist in maintaining the lower section of the wall in alignment. 90

8. A furnace comprising a stoker, a wall built in sections, one of which sections is supported on the stoker, a beam independent of the stoker upon which the upper section of the wall is supported, special tiles in the 95 lower section, and metallic tie pieces engaging said tiles and said beam to assist in maintaining the lower section of the wall in alignment, the projecting ends of said tie pieces being in an inclosed space, and means 100 for ventilating said space to prevent overheating.

9. In a boiler furnace a stoker, a front wall extending across and above the stoker, said wall being divided into sections by a 105 horizontally extending slip joint, and means for supporting the two sections independently of each other, the lower section being supported on the stoker mechanism.

10. In a boiler furnace a stoker, a front 110 wall extending across and above the stoker, said wall being divided into sections by a horizontally extending slip joint, means for supporting the two sections independently 115 of each other, and means for holding the lower section in alignment.

11. In a boiler furnace a stoker, a front wall extending across and above the stoker, said wall being divided into sections by a horizontally extending slip joint, means for 120 supporting the two sections independently of each other, and means exterior to the lower section arranged to hold it in alignment.

12. In a boiler furnace a stoker, a front 125 wall extending across and above the stoker, said wall being divided into sections by a horizontally extending slip joint, means for supporting the two sections independently 130 of each other, and means secured to the sup-

porting means for the upper wall section and arranged to hold the lower wall section in alinement.

13. In a boiler furnace a stoker, a front wall extending across and above the stoker, said wall having a horizontally extending slip joint, the lower section being supported on the stoker.

14. In a boiler furnace a stoker, a front wall extending across and above the stoker, said wall having a horizontally extending

slip joint, the lower section being supported on the stoker, and external means for holding the lower wall section in alinement.

In testimony whereof I have hereunto 15 signed my name in the presence of two subscribing witnesses.

DAVID S. JACOBUS.
